SOAP HOLDER

Joseph W. Stevens, Glens Falls, N. Y.

Application December 17, 1941, Serial No. 423,286

7 Claims. (Cl. 45—28)

This invention relates to holders for a cake or bar of soap and it is the principal object of the invention to provide a holder having suction means to mount the holder on a supporting surface, such as the side of a bath-tub or the wall of a bath-room adjacent to the bath-tub or wash-bowl, and adjustable means to releasably retain a bar of soap on the holder with an exposed surface of the bar of soap extending parallelly of the supporting surface whereby a wash-cloth or bath-cloth may readily be wiped or rubbed over said exposed surface of the soap to gather or remove soap therefrom, and the soap will be uniformly used across said surface.

It is another object of the invention to provide a holder for a bar or cake of soap having an arrangement of parts which may be manufactured and assembled at a low cost.

It is a further object of the invention to provide the holder with soap retaining means arranged with actuating means adapted to co-act with the holder to lock the retaining means against accidental movement.

Further objects and advantages of the invention will be set forth in the detail description of the embodiment of the invention.

In the drawing accompanying and forming a part of this application,

Figure 1 is an end elevational view of the holder having a bar of soap retained thereon and mounted on a supporting surface.

Figure 2 is a top plan view of the holder with a bar of soap removed therefrom and soap retaining means shown in full lines as actuated in position to permit the removal or positioning of a bar of soap from or on the holder, and shown in dot and dash lines in soap securing position.

Figure 3 is a bottom plan view of the holder with the soap retaining means actuated to soap releasing position.

Figure 4 is a sectional view of the holder taken on the line 4—4 of Figure 2 looking in the direction of the arrows.

Figure 5 is a fragmentary view of actuating means for the soap retaining means in position actuating the retaining means in soap retaining position.

Figure 6 is a perspective view of actuating means for the soap retaining means with the parts thereof separated from each other.

In carrying out the embodiment of the invention illustrated in the accompanying drawing, there is provided a holder or support for a bar of soap S comprising a rectangular plate 6 slightly larger than the size and shape of a new bar

10 of soap and having the corners cut diagonally to form oblique edges 7 and the edge portions of the plate between said oblique corner edges 7 bent upwardly from a face of the plate, as shown at 8, to form a recessed face on the plate for supporting a bar of soap, the bent or flange portions 8 being of a depth to retain the soap against sliding movement on the plate and to form the recessed face of a size and shape substantially the same as a new bar of soap with the flange portions 8 engaging the sides of the bar of soap, as shown in Figure 1. The plate may be of any suitable material, such as metal or plastic material, but a non-corrosive surfaced metal is preferable due to the cheapness in working and forming the plate in the manner hereinafter described.

The plate is adapted to be releasably mounted on a supporting surface s, such as the side of a bath-tub, or the wall of a bath-room adjacent to a wash-bowl, bath-tub or shower, by suction means comprising rubber suction or vacuum cups 9 of usual construction having a metal shank 10 fixedly embedded therein and secured to the plate 6 by engaging the shank in a suitable opening in the plate and securing the shank in the opening by soldering or peening the end of the shank over the recessed face of the plate. The shanks 10 are inserted in the plate 6 from the face opposite the recessed face of the plate to have the suction cups 9 project from said opposite face, and in the present illustration of the invention, there are provided four suction cups with each cup mounted adjacent to an oblique corner edge 7, whereby the plate is firmly mounted on the supporting surface s. When the plate is mounted on the supporting surface s by the suction cups 9, the recessed face of the plate is exposed and extends in a plane parallel to the supporting surface.

40 A bar of soap S is engaged on the exposed recessed face of the plate 6 and releasably retained thereon by a pair of clamping or jaw members comprising an elongated body 11 of relatively stiff material, such as a strip of suitable metal, having at one end a transversely extending head 12 arranged with a series of pointed teeth 13 at the free end and said head being bent upon itself to U or channel shape in cross section, as shown in Figure 4, with the teeth 13 extending in parallel spaced relation to the portion of the head connected to the body 11. The bodies 11 are slidably supported on the face opposite to the recessed face of the plate 6 by loop or yoke portions 14 formed

from the material of the plate by a pair of spaced slits extending transversely of the longitudinal axis of the plate and terminating equal distances from and on the opposite sides of said axis and bending the material between said slits from the opposite face of the plate, as shown in Figure 4. The yokes 14 are positioned adjacent to the opposite ends of the plate 6 and the bodies 11 are mounted in said yokes to position the teeth 13 to extend in a plane parallel of the recessed face of the plate and slightly above the flanges 8 at the opposite ends of the plate to adapt the teeth to engage and bite into the end edge portions of the bar of soap S on the plate.

The actuation of the jaw bodies 11 in a direction toward each other will move the jaw teeth 13 into the bar of soap to retain the soap on the plate 6 and the actuation of jaw bodies 11 in a direction from each other moves the jaw teeth 13 from the bar of soap to permit the removal of a used bar of soap from the recessed face of the plate 6 and the engagement of a fresh bar of soap on said face. The jaw members are jointly actuated by suitable means, such as a lever, comprising a rod 15 having one end bent laterally to form a manipulating portion 16 having the free end curled inwardly upon itself, as shown at 17. The rod 15 is rotatably supported from the face opposite the recessed face of the plate 6 by an ear 18 severed from the material of the plate and bent from the opposite face adjacent to a side edge of the plate and a pair of ears 19 severed from a portion of the material of the plate extending on the transverse axis of the plate and transversely of the longitudinal axis of the plate with the free ends of the ears 19 on said longitudinal axis and said ears bent laterally from the opposite face of the plate on opposite sides of the longitudinal axis, as shown in Figure 3. The ears 18 and 19 are arranged with aligned openings to rotatably support the rod 15 at the opposite end portions thereof. The inner ends of the jaw bodies 11 are operatively and eccentrically connected to the rod 15 by a crank element comprising a flat member 20 having a pair of spaced ears on the opposite sides thereof curled to circular shape to form eyelets 21 and is fixed to the portion of the rod positioned between the ears 19 by engaging said member in a slot 22 in the end opposite the bent end 16 of the rod, as shown in Figure 6, and the member 20 is fixed in said slot by rivets engaged in aligned openings in the slotted end of the rod and the member 20, as shown at 23. The member 20 is pivotally connected to the jaw bodies 11 by a pin 24 engaged and fixed in each pair of eyelets 21 by clamping the material of the eyelets to the pin, and bending the inner end of each jaw member 11 about the pin, as shown at 25 in Figure 4. The rotation of the rod 15 in an arc intermediate 90 and 180 degrees by actuating the manipulating portion 16 from the dot and dash line position to the full line position shown in Figure 2 will move the member 21 to the position shown in Figure 3 with the jaw teeth 13 spaced laterally from the end flanges 8, and the actuation of the manipulating portion 16 from the full line position to the dot and dash line position shown in Figure 2 will position the pins 24 in reverse relation to that shown in Figure 3 with the inner end portions of the jaw bodies 11 extending transversely above and below the rod 15, as shown in Figure 5, and the jaw teeth 13 extending over the end flanges 8 and the recessed face of the plate 6,

as shown in dot and dash lines in Figure 2. Washers 26 are engaged on the rod 15 between the ears 19 and the opposite ends of the member 20 to take up longitudinal movement of the member 20 and facilitate rotation of the rod 15.

The jaw members are locked in either of their extreme actuated positions by actuating the manipulating portion 16 downwardly beyond the plate to position the curled end 17 below the plate, so that a pulling force applied to the jaw members will move the curled end 17 against the bottom of the plate and prevent further rotation of the rod 15.

The position of the manipulating portion 16 relative to the plate 6 will permit the actuation of the jaws 13 and the removal of a used bar of soap from the recessed face of the plate and the positioning of a fresh bar of soap on said face without requiring the removal of the plate 6 from the supporting surface s.

Having thus described my invention, I claim:

1. In a holder for a bar of soap, a plate having the front face arranged to support a bar of soap, means fixed on the back face of the plate to mount the plate on a supporting surface, a pair of members having jaws arranged at one end, slidably mounted on the back face of the plate and the jaws positioned in a plane extending parallelly of and spaced from the soap supporting face of the plate to engage opposite ends of the bar of soap on the plate, and means rotatably mounted on the back face of the plate connected to the ends of the pair of members opposite the jaw ends thereof and manually operative to actuate said members to move the jaws of said members toward and away from opposite ends of the bar of soap on the plate.

2. A holder for a bar of soap as claimed in claim 1, wherein the actuating means for the jaw members comprises a rod rotatably supported from the back face of the plate and having a portion pivotally and eccentrically connected to the jaw members and a manipulating portion arranged to engage a side edge portion of the plate and lock the jaw members against movement.

3. A holder for a bar of soap as claimed in claim 1, wherein the actuating means for the jaw members comprises a rod having one end bent laterally from the body thereof and the body rotatably supported on the back face of the plate with the laterally bent portion projecting from a side edge of the plate, and a member fixed on the rod having a pair of ears projecting from opposite sides thereof and said ears pivotally connected to the ends of the jaw members opposite the jaw ends of said members.

4. A holder for a bar of soap as claimed in claim 7, wherein the actuation of the rotatable member through an arc of around 180 degrees positions the manipulating portion in engagement with the back face of the plate and locks the jaw members against movement.

5. In a holder for a bar of soap, a plate to support a bar of soap on the front face thereof, and means mounted on the back face of the plate adapted to engage and support the plate on a supporting member, members mounted on the back face of the plate with one end of one member extending beyond one end of the plate and the end of the other member extending beyond the opposite end of the plate and said ends of said members arranged with jaws disposed at and having movement relative to the front face of the plate to grip and hold a bar of soap to the

front face of the plate, and a crank element rotatably mounted on the back face of the plate connected to the ends of said members opposite the jaw ends manually rotatable to simultaneously actuate said members to move the jaws into and out of gripping engagement with a bar of soap disposed relative to the face of the plate.

6. In a holder for a bar of soap, a plate the front of which is adapted for the engagement of a bar of soap, a pair of members mounted on the back face of the plate with one end of said members extending beyond the opposite ends of the plate and said ends arranged with jaws disposed at the front face of the plate and having movement toward and away from each other to grip opposite portions of a bar of soap disposed at the front face of the plate and holding the bar of soap to the plate, and means rotatably mounted on the back face of the plate connected to which the opposite ends of said pair of members are eccentrically connected, and said means normally rotatable to simultaneously actuate said pair of members to move the jaws into gripping engagement with the bar of soap disposed rela-

tive to the front face of the plate and retain said members in said portion.

7. In a holder for a bar of soap, a plate having the edges flanged laterally from the front face thereof to be disposed at the sides of a bar of soap supported on said face, means mounted on the back face of the plate to mount the plate upon a supporting surface, a pair of elongated members slidably mounted on the back face of the plate with one end extending beyond the ends of the plate and arranged with jaws and the jaws positioned in a plane extending parallel of and spaced from the flanged front face of the plate to engage opposite ends of a bar of soap on said flanged face of the plate, and a member having a manipulating portion rotatably mounted on the back face of the plate to which the ends of said members are eccentrically connected and adapted to be actuated through an arc of more than 90 degrees and less than 180 degrees by the manipulating portion to move the jaws into and out of engagement with a bar of soap on the flanged face of the plate.

JOSEPH W. STEVENS.
